UNITED STATES PATENT OFFICE.

BANNY GOLDSTEIN, OF BROOKLYN, NEW YORK.

VENTILATING-WINDOW-LOCKING DEVICE.

Application filed August 2, 1924. Serial No. 729,669.

To all whom it may concern:

Be it known that I, BANNY GOLDSTEIN, a citizen of Rumania, residing at 144 Varet Street, Brooklyn, in the county of Kings, city and State of New York, have invented certain new and useful Improvements in Ventilating-Window-Locking Devices, of which the following is a specification.

My invention relates to a new and improved form of ventilating window locking device.

One of the objects of my invention is to provide a locking device which can be readily applied to any window, so as to securely lock said window when it is partly open, so as to permit safe ventilation.

Another object of my invention is to provide a locking device which can be readily removed and replaced without the necessity of removing any fixed parts, manipulating keys, etc.

Another object of my invention is to provide a locking device which will permit the use of the ordinary window lock, when the window is closed.

Another object of my invention is to provide a locking device which can be removed only at the inside of the window, and when the window is closed.

Other objects of my invention will be set forth in the following description and drawings, which illustrate a preferred embodiment thereof.

Fig. 1 is an elevation, partly in perspective, showing the inner side of the closed window.

Fig. 2 is a view similar to Fig. 1, showing the window partially open.

Fig. 3 is a section on the line 3-3, the locking member being shown in perspective.

The device is shown applied to a window of any ordinary type, having a lower or inner sash 11 and an upper or outer sash 10.

The sashes 10 and the frame of the window above sash 11 have studs 15 and 14 rigidly connected thereto. The said studs are rigidly secured to metal base members which are rigidly connected by means of screws to the proper parts. The window has the ordinary lock 12.

A locking member or device is provided with a short upper slot 17 and a long lower slot 16, through which the studs 15 and 14 can be caused to project when the window is

closed, so that the shanks of said studs are free to slide in said groove. The heads of said studs are longer than the widths of said grooves so that the member 13 can be placed upon the shanks of the studs, and removed from the studs, only when the window is closed, as shown in Fig. 1.

When the upper sash 10 is lowered, the locking device 13 turns on the shanks of the studs 14 and 15, until the leg 18 rests upon the top of lower sash 11.

It is then impossible to further lower the upper sash 10, or to remove the locking device 13, because the heads of the studs 15 and 14 are now inclined to their respective grooves 16 and 17. The parts are so designed that the upper sash cannot be lowered sufficiently to enable the entrance of any person.

Hence, ventilating and secure locking are simultaneously provided, since the member 13 cannot be removed until the window is closed, when the member 13 can be readily removed and replaced.

According to my invention, the locking member is so designed, that the upper part of the window cannot be lowered more than about six inches when it is held against further downward movement.

I have shown a preferred embodiment of my invention, but it is clear that numerous changes and omissions could be made without departing from its spirit.

I claim:

1. A locking device for a window having upper and lower sashes slidable in a frame, comprising a first stud having a head and a shank secured to the upper sash, a second like stud fixed to said frame above the top of said lower sash, and a locking device having grooves through which the heads of said studs are adapted to project and in which the shanks of said studs are adapted to slidably fit, the lengths of the heads of said studs being greater than the widths of their respective grooves, said locking device being adapted to abut the top of said lower sash when said upper sash is lowered, to prevent further lowering of said upper sash.

2. A device according to claim 1, in which the said grooves are of unequal length, and the first stud is adapted to project through the shorter groove.

3. A locking device for a window having

upper and lower sashes slidable in a frame, comprising projecting members connected to the upper slidable sash and to said frame, and a locking member slidably and turnably mounted on said projections the shape of said locking member being such that a portion thereof is adapted to abut said lower

sash when it is caused to move by the lowering of said upper sash, so as to prevent further movement of said upper sash. 10

In testimony whereof I hereunto affix my signature.

BANNY GOLDSTEIN.
